(57) **CLAIM**

The ornamental design for a combined dispenser comprising a container for moist towelettes, a bar for holding a roll of toilet paper and an extendible tray in which other objects can be placed, as shown and described.

DESCRIPTION

FIG. 1 is a perspective view of the preferred embodiment of the present invention of a combined dispenser comprising a container for moist towelettes, a bar for holding a roll of toilet paper and an extendible tray in which other objects can be placed, showing my new design;

FIG. 2 is a front elevational view;

FIG. 3 is rear elevational view;

FIG. 4 is a side elevational view, when viewed from the right side;

FIG. 5 is a side elevational view, when viewed from the left side;

FIG. 6 is a top plan view;

FIG. 7 is a bottom plan view;

FIG. 8 is a front elevational view showing the extendible tray extended for a given distance below the dispenser for a container for moist towelettes; and,

FIG. 9 is a front elevational view showing the extendible tray at its maximum extension below the container for moist towelettes.
